Fig. 5.

FIG. 1 is a top plan view of a furniture foot or the like, showing my new design;

FIG. 2 is a side elevational view thereof;

FIG. 3 is an end elevational view thereof;

FIG. 4 is a perspective view thereof, from an upper aspect; and

FIG. 5 is a perspective view thereof, from a lower aspect.

The end and side portions not shown are mirror images of the respective end and side portions shown.

The stippling in the accompanying illustrations shows portions of the design which are of a darker color than the remaining portions of the design.

The dominant features of the design are shown in full lines.

I claim:

The ornamental design for a furniture foot or the like, substantially as shown and described.
